UNITED STATES PATENT OFFICE.

DILLON BEEBE, OF NEWARK, NEW JERSEY.

FAUCET-BUNG.

SPECIFICATION forming part of Letters Patent No. 628,298, dated July 4, 1899.

Application filed December 23, 1898. Serial No. 700,185. (No model.)

To all whom it may concern:

Be it known that I, DILLON BEEBE, a citizen of the United States, residing at Newark, in the county of Essex and State of New Jersey, have invented certain new and useful Improvements in Faucet-Bungs; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to certain improvements in that class of faucet-bungs for ale or beer barrels and the like, represented by the one shown in my prior faucet bung or valve, granted December 15, 1896, No. 573,254, the objects of the present improvements being to reduce the cost of construction, facilitate manufacture, and enable a more exact and perfect valve body and seat to be formed, whereby the valve will be rendered more perfect in its operations and functions; to secure greater strength to resist the strain occasioned when the bung-body is screwed into the bung-hole of the package, and to secure other advantages and results, some of which may be referred to hereinafter in connection with the description of the working parts.

The invention consists in the improved faucet bung or valve and in the arrangements and combinations of parts of the same, all substantially as will be hereinafter set forth, and finally embraced in the clauses of the claim.

Referring to the accompanying drawings, in which like letters of reference indicate corresponding parts in each of the several views, Figure 1 is a central longitudinal section of the improved faucet-bung. Fig. 2 is a plan thereof. Fig. 3 is a plan of a certain rear section of the faucet-bung body. Fig. 4 is a sectional view of the front section of said body, and Fig. 5 is a side elevation of said rear portion.

In said drawings, *a* indicates the body of the faucet-bung, which is in sections *a'* *a''*, the upper or front section *a'* being threaded exteriorly and provided interiorly with a key-seat *a³*, in which may be arranged a packing *b*. The said front section is chambered above

said seat to receive the hub *c'* of the key *c*, and the walls of the chamber are provided with wide and narrow key-inlet slots *a⁴* *a⁵* to receive the correspondingly narrow and wide lugs *c²* of said key, whereby the said key can only be inserted within said chamber when in position to properly engage the triangular or otherwise shaped valve-head *f'* of the valve-body *f*.

The walls of the chamber within the section *a'* are also provided with slightly-inclined grooves *a⁶*, by means of which the key *c* at the bottom of its hub is brought into impervious relation to the faucet-bung in the usual manner. At the lower or rear end of the said front section the same is recessed, as at *a⁷*, Fig. 4, to receive the lower or rear section, the latter fitting into said front section rather loosely to form a small annular chamber to receive solder or brazing metal by which the sections are rigidly and strongly united. The side walls of the recess are provided preferably with shallow grooves *a⁸* to facilitate a running of the solder into said annular chamber and to secure perfect and strong union of parts.

To secure an exact disposition of the lower or rear section upon the front section, so that the wide and narrow grooves *a⁴* *a⁵* of the upper or outer section will with facility and without any particular care and study involving an expenditure of considerable time be brought into proper relationship to the ports or valve-openings *a¹¹* of the lower section, the side walls of the front section within said recess *a⁷* are provided with inwardly-extending wide and narrow lugs *d* *d'*, and the rear section *a²* is provided at its forward end with notches *a⁹* *a¹⁰*, which also vary in width in correspondence with the lugs *d* *d'*, the said lugs of the upper section being so disposed that they will enter the notches of the rear or lower section and properly bring the valve-openings of said rear section into operative relation with the slots or grooves *a⁴* *a⁵* of the front section and enable the key *c*, when inserted in said front section, to properly engage the valve-head and effect an opening of the said valve-ports.

The joint formed between the sections *a'* *a''* is formed at a point at which all torsional strain, such as is brought upon the body in

the act of screwing it into the barrel or keg, will be brought upon the one front section, the rear section being relieved of such strain, and thus there is no danger of forcing the 5 section providing the bearing for the wrench or screwing-tool from the section having the outer screw-threads.

At the rear or lower end of the rear section a^2 the same is provided with a valve-seat a^{12} 10 on opposite sides thereof adapted to receive the disk-valve f . This said disk-valve f comprises, preferably, two disks $f^2 f^3$, connected to and operated by means of the head f' in the manner shown and described in my prior 15 patents. Said disks engage the opposite sides of the seat a^{12} , each forming a close joint to prevent the escape of fluid when the valve is closed.

Having thus described the invention, what 20 I claim as new is—

1. The improved faucet-bung, comprising a front section a' , exteriorly threaded, interiorly provided with a key-seat and means for holding the key in place thereon and at 25 the rear or back having a recess with lugs formed therein, and a rear or inner section

a^2 , having a valve-seat and valve and at the front edge having notches to receive said lugs, said sections being soldered, braced or imperviously joined together, substantially 30 as set forth.

2. The improved faucet-bung, comprising a front section a' , having the key-seat, and a rear section a^2 , having a valve-seat and valve, one section fitting the other and having 35 notches and lugs to resist torsional strain, and means for fastening said parts together, substantially as set forth.

3. The improved faucet-bung comprising a front section a' having a key-seat and a rear 40 section a^2 , having a valve-seat and valves, one section fitting the other and having wide and narrow notches and lugs and brazing metal or solder joining said sections imperviously substantially as set forth. 45

In testimony that I claim the foregoing I have hereunto set my hand this 17th day of December, 1898.

DILLON BEEBE.
